MANUFACTURE OF CARD MOUNTINGS

Filed Jan. 9, 1932

UNITED STATES PATENT OFFICE

LEONARD A. MACLEAN, OF READING, MASSACHUSETTS

MANUFACTURE OF CARD MOUNTINGS

Application filed January 9, 1932. Serial No. 585,655.

This invention relates to mount members attachable to a backing to receive and confine upon the backing, corners of a rectangular article or card, such as a photographic print.

The chief object of the invention is to provide as an article of manufacture, and at a very small expense, a blank containing material for a plurality of corner mount members, and adapted to be conveniently and accurately converted by a user into a plurality of said members each including a triangular pocket having a free edge on its hypotenuse defining a pocket mouth, and an angular neck defining a closed pocket end or bottom, each mount member including also a gummed attaching flange located outside the pocket and joined to and projecting from the angular neck thereof and attachable to a backing, the flange and pocket being in parallel planes, said corner members being producible by severing the blank on predetermined straight lines by a simple and readily available instrumentality such as ordinary scissors or shears.

Of the accompanying drawings forming a part of this specification,—

Figure 1 is a side view of a blank convertible into a relatively small number of corner members.

Figure 2 is a section on line 2—2 of Figure 1.

Figure 3 is a side view of a blank convertible into a larger number of corner members.

Figure 4 shows a portion of the blank shown by Figure 3 provided with cut indicating marks.

Figure 5 shows in perspective one of the completed corner members attached to a backing.

Figure 6 is a side view showing a mount, four of the corner members, produced by subdividing the blank, attached to the mount, and a card confined on the mount by the corner members.

Figure 7 is a fragmentary perspective view similar to Figure 5 showing a portion of the confined article.

Figure 8 is a view similar to Figure 1 showing a modified form of the blank.

Figure 9 is a side view of a corner member produced by severing the blank shown by Figure 8.

Figure 10 is a fragmentary side view showing the corner member shown by Figure 9 attached to a backing, and a card portion confined by the corner member.

Figure 11 is a side view of a portion of a female embossing and printing die.

Figure 12 is a section on line 12—12 of Figure 11.

Figure 13 is a side view of a portion of a completed blank as printed by the female die.

The same reference characters indicate the same parts in all of the figures.

I will first describe the preferred embodiment shown by Figures 1 to 7, inclusive.

My improved blank is made from a substantially rectangular sheet of material such as paper, having a dried gum coating 12 (Figure 2) on one of its sides. Said sheet may be relatively narrow as shown by Figure 1, and provided with one row of the bosses next described, or may be wider and provided with a plurality of said rows as shown by Figure 3.

I first emboss the sheet by suitable dies, to form thereon a plurality of substantially square bosses 13 which may be arranged in a single row, as shown by Figure 1, or a plurality of rows as shown by Figure 3, the bosses being spaced apart so that they are surrounded by a flat portion of the blank, said portion and the bosses being in parallel planes. The edges of the bosses are parallel with the edges of the blank and the bosses project from the side of the flat portion opposite the coated side and are stiffened by the gum coating.

The bosses 13 provide material for the triangular pockets, and the flat portion of the blank provides material for the angular flanges hereinafter described. The blank is preferably provided with marks printed thereon to indicate the location of straight cuts made by a cutting tool employed to subdivide the blank.

The arrangement is such that when the blank shown by Figure 3 is subdivided by straight cuts indicated by dotted lines *a* ex-

tending diagonally of the blank and between diagonally opposite corners of the bosses 13, other straight cuts indicated by dotted lines *c* extending crosswise of the blank and between adjacent bosses, and other straight cuts indicated by dotted lines *e* extending lengthwise of the blank, the triangular corner members shown by Figures 5, 6 and 7 are produced.

- 10 The narrow blank shown by Figure 1 requires subdivision only on the lines *a* and *c*. The location of said cuts is preferably indicated by marks *h* printed on the blanks as shown by Figure 4. Said marks are shown 15 by solid lines and are practically obliterated by the operation of subdividing the blank by instrumentalities such as ordinary scissors or shears.

Each corner member produced as above described includes a triangular pocket 13^a constituting one-half of a boss 13, said pocket having a free edge 13^b on its hypotenuse defining the mouth of a pocket adapted to receive a corner of a mounted article or card *g*.

- 20 The pocket has also a right angled neck 13^c, defining the closed end or bottom of the pocket. A corner member thus provided with a pocket, is provided also with an angular attaching flange 16 joined to and projecting from the neck 13^a and formed from a part of the flat portion of the blank. Said neck offsets the pocket from the flange so that the pocket and flange are in parallel planes. The flange has a portion of the gum coating 12 on its inner side so that it is attachable to a backing *f*. The angular flange 16 has a right angled salient outer edge, and a reentrant inner edge joined to the neck 13^c.

40 The blank shown by Figure 8 and a corner member produced therefrom shown by Figures 9 and 10, differ from the blank and corner member above described, in that the edges of the bosses 13 are oblique to the edges of the blank. The locations of straight cuts 45 converting the blank into corner members are indicated by *i* and *j* in Figure 8. The attaching flange 16^a of each corner member is approximately rectangular and oblong as shown by Figures 9 and 10, and extends obliquely on the backing *f* as shown by Figure 10.

55 It will be seen that blanks characterized as described are very inexpensive and prepared by the simple operations of embossing sheets of gummed paper and printing the indicating marks thereon. The embossing operation is performed by a male and a female die acting on opposite sides of the blank, and the printing operation may be performed 60 by adapting the female die to print the lines *h* during the embossing operation. The female die may be also adapted to apply to the flanges 16, a tint or color contrasting with that of the paper, and thus impart a variegated effect to the outer sides of the corner

member, the pocket member 13^a retaining the color of the paper.

A portion of the female die *k* is shown by Figures 11 and 12, the die having a flat face *m* interrupted by the square cavities *n* into which parts of the blank are forced by corresponding projections on the male die. The face *m* is interrupted also by grooves *o* arranged as shown by Figure 11. The die surface *m* may be inked before the embossing operation and becomes a printing surface adapted to apply a film of printing ink of any desired color to the flat surfaces of the blank surrounding the bosses 13, said film being interrupted by the grooves *o* so that the embossing operation is also a printing operation causing the lines *h* shown in black by Figure 4 to appear as lines of the color of the paper, as shown by Figure 13.

I have thus disclosed the female die to show the facility with which the blank may be marked by printing to guide a hand tool in subdividing the blank into corner members.

The embossed blanks may be supplied as articles of manufacture and sale for use by individuals desiring only to subdivide the blanks by hand tools into small numbers of sets of corner members.

It is obvious, however, that blanks characterized as stated may be converted into corner members in large quantities by a suitable automatic machine adapted to rapidly subdivide the blanks for quantity production.

I claim:

1. As an article of manufacture a rectangular sheet having a gum coating on one side and including a plurality of spaced apart square bosses offset from its opposite side and stiffened by said coating, said sheet being divisible into a plurality of pocketed corner members by straight cuts extending between diagonally opposite corners of the bosses, and other straight cuts extending between adjacent bosses, each of said members including an attaching flange and a triangular pocket constituting one-half of a boss, and having a free mouth-defining edge on its hypotenuse and a right angled bottom-defining neck joined to the flange, the pocket and flange being in parallel planes.

2. As an article of manufacture a rectangular sheet gummed on one side and including a plurality of spaced apart square bosses offset from its opposite side and stiffened by said coating, the edges of said bosses being parallel with the edges of the sheet, said sheet being divisible into a plurality of pocketed and flanged corner members by straight cuts diagonal to the sheet and extending between diagonally opposite corners of the bosses, and other straight cuts extending parallel with edges of the sheet between adjacent bosses, each of said members including an angular attaching flange having a salient

outer edge and a reentrant inner edge, and a triangular pocket constituting one-half of a boss and having a free mouth-defining edge on its hypotenuse and a right angled bottom-defining neck joined to the reentrant edge of the flange, the pocket and flange being in parallel planes.

3. As an article of manufacture a rectangular sheet having a gum coating on one side and including a plurality of spaced apart square bosses offset from its opposite side and stiffened by said coating, said sheet being divisible into a plurality of pocketed corner members by straight cuts extending between diagonally opposite corners of the bosses, and other straight cuts extending between adjacent bosses, each of said members including an attaching flange and a triangular pocket constituting one-half of a boss, and having a free mouth-defining edge on its hypotenuse and a right angled bottom-defining neck joined to the flange, the pocket and flange being in parallel planes, the sheet being provided with printed marks arranged to indicate the predetermined location of the several straight cuts.

4. The method of making pocketed corner members consisting in embossing a rectangular gummed sheet to form spaced apart square bosses offset from one side of the sheet, and subdividing the sheet by straight cuts extending between diagonally opposite corners of the bosses, and other straight cuts extending between adjacent bosses, thereby forming a plurality of corner members, each including an attaching flange and a triangular pocket constituting one-half of a boss, and having a free mouth-defining edge on its hypotenuse and a right angled bottom-defining neck joined to the flange, the pocket and flange being in parallel planes.

5. The method of making pocketed corner members consisting in embossing a rectangular gummed sheet, and at the same time printing the sheet to provide marks indicating the location of straight cuts extending between diagonally opposite corners of the bosses, and other straight cuts extending between adjacent bosses, and subdividing the sheet on lines indicated by said marks, thereby forming a plurality of corner members each including an attaching flange and a triangular pocket constituting one-half of a boss, and having a free mouth-defining edge on its hypotenuse and a right angled bottom-defining neck joined to the flange, the pocket and flange being in parallel planes.

In testimony whereof I have affixed my signature.

60 LEONARD A. MACLEAN.
